UNITED STATES PATENT OFFICE.

ANDREW F. CURTIN, OF MEDFORD, MASSACHUSETTS.

FLUSHING-VALVE FOR WATER-CLOSETS.

1,285,055.

Specification of Letters Patent. Patented Nov. 19, 1918.

Application filed May 25, 1918. Serial No. 236,517.

To all whom it may concern:

Be it known that I, ANDREW F. CURTIN, a citizen of the United States, residing at Medford, in the county of Middlesex and 5 State of Massachusetts, have invented certain new and useful Improvements in Flushing-Valves for Water-Closets; and I do hereby declare the following to be a full, clear, and exact description of the invention, 10 such as will enable others skilled in the art to which it appertains to make and use the same.

The present invention relates to an improvement in flushing valves for water 15 closets.

The object of the invention is to improve upon the construction and arrangement of the parts of a water closet flushing valve in order to produce a more durable and, consequently, a more efficient flushing valve than has heretofore been produced. A further object of the invention is to improve upon the construction of a flushing valve to the end that the cost of production or manufacture 20 thereof may be reduced. To the accomplishment of these objects and such others as shall hereinafter appear, the present invention consists in the improved flushing valve particularly pointed out in the appended 25 claims, a specific embodiment of this flushing valve being described in the following specification.

The preferred form of the invention is illustrated in the accompanying drawing, in 30 which Figure 1 is a vertical section of the improved flushing valve, and Fig. 2 is a bottom plan view thereof on a reduced scale. In its general principles of construction and mode of operation, the valve illustrated in 35 the drawing and chosen for the application thereto of the principles of the present invention is substantially like the flushing valve shown and described in the patent to Curtin No. 1,263,534 granted April 23, 1918. 40 This flushing valve comprises a hollow body portion 5 through which the water passes from the tank in which the flushing valve is located to the closet bowl. The body portion 5 is furnished with the usual spud 6 for insertion through a hole in the bottom of the tank and with a hollow arm 7 for supporting the overflow pipe. The upper end 45 of the body portion 5 opens into the tank 50

and constitutes the inlet of the flushing valve and the lower end or spud 6 of the body portion 55 constitutes the outlet of the flushing valve.

The valve proper consists of a flat valve disk 9 carried on the bottom of a hollow float member 10 and is adapted to seat upon 60 the upper rim 11 of the body portion 5. The valve float 10 is provided with an eye-piece or nut 12 for the accommodation of a chain or rod by which the flushing valve is manipulated. Fixed within the body portion 5 by 65 means of a transverse support 14 is a dash pot 15 closed at its lower end and within which a piston or plunger 16 is adapted to slide freely. The plunger 16 is connected by a rod 17 with the float 10 and is guided 70 in its up and down movement by a nut 18 screwed onto the upper end of the dash pot 15. Apertures 20 are formed in the upper part of the dash pot 15 to permit water to flow into the dash pot when the 75 valve 9 is unseated.

The mode of operation of the flushing valve thus briefly and generally described is as follows: So long as the tank is full of water, the valve 9 is held seated by the 80 weight of the parts connected with the valve and by the pressure of the water in the tank on the float 10. The flushing of the bowl is accomplished by lifting the float by manipulation of the usual chain or lever, where- 85 upon the water in the tank flows through the body portion 5 to the bowl. The lifting of the float brings the plunger 16 into the upper end of the dash pot 15 and just above the apertures 20 so that the water can flow down 90 into the dash pot below the plunger. The buoyancy of the float when it has been lifted keeps the valve 9 unseated until the water in the tank has receded to a predetermined level, whereupon the action of the plunger 95 on the water in the dash pot assures the gradual and silent closing of the valve and a proper refilling of the bowl, all occurring substantially as in the flushing valve shown and described in said patent.

The improvements in water closet valves as proposed by the present invention consist in the construction by virtue of which the various parts of the flushing valve are formed, assembled and permanently held together so as to constitute a durable flushing 100 105

valve capable of withstanding long and severe use without impaired efficiency. This principle of construction is described as follows: The upper part of the bell 10 of the valve float is drawn or spun into form. The hole in the top of the bell through which the upper end of the plunger rod 17 passes is punched in from the outside in such wise as to leave a burr 22 therein so as to provide a lip or flange to be threaded. The bottom of the valve float is closed by a plate 24 which has an upturned marginal flange 25 to receive tightly the rim of the bell 10 and an internally downturned flange 26 surrounding a central aperture 27. The rim of the bell 10 is provided with two grooves 29, which when the bell is joined to the plate 24, are adapted to receive white lead or the like to establish a water tight joint between the rim of the bell and the flange 25. It is apparent that the grooves 29 could be dispensed with, or that the rim of the bell and the flange 25 could be in threaded connection. Into the downturned flange 26 is screwed a relatively heavy centerpiece 28, preferably made as a casting, and having a threaded central hole into which the plunger rod 17 is screwed. The bottom end 30 of the centerpiece 28 extends below the downturned flange 26 to accommodate a nut 31 which performs the double function of holding the leather valve disk or washer 9 up against the under side of the bottom plate 24 and holding the centerpiece in place. This centerpiece 28 is in the form of an inverted cup and up into this centerpiece the upper part of the dash pot 15 extends. An aperture 33 is cut in the side of the centerpiece to permit any water that might find its way into the hollow float to flow out therefrom, down through the body portion of the valve. The eye-piece or nut 12 screws onto the projecting end of the plunger rod 17 and takes against the top of the bell 10.

During the process of assembling the parts of the flushing valve, the centerpiece 28 is first screwed into the bottom plate 24 from the top thereof, as appears from the drawing, and then the bell 10 is forced into the marginal upturned flange 25. The nut 18 is next passed over the upper end of the plunger rod 17 and then the plunger rod is simultaneously screwed into both the centerpiece and the top of the bell until the shoulder 35 on the rod presses firmly against the under side of the central portion of the centerpiece. The eye-piece 12 is then screwed onto the projecting end of the rod 17 and screwed down firmly against the top of the bell so as thereby to firmly attach it to the bell without distortion of the bell or subjecting it to any crushing stresses, as the pressure exerted by the eye-piece on the bell is taken by the thread on the upper end of

the rod 17. The valve disk 9 is then placed on the bottom of the bottom plate 24 over the downturned flange 26 and the holding nut 31 is screwed onto the projecting end 30 of the centerpiece. The plunger 16 may now be inserted into the dash pot 15 and the nut 18 screwed into the upper end of the dash pot, thereby completing the assemblage of the parts. It is apparent that if at any time the bell should become injured the eyepiece 12 may be taken off, so that the bell can be removed from the flange 25 and unscrewed from the end of the plunger rod 17 without disturbing the other parts of the valve. In this connection it is to be noted that the threads in the flange 26, the central hole in the centerpiece 28, and the hole in the top of the bell are all of the same pitch.

From the foregoing description it is now apparent that the flushing valve construction of the present invention presents several features of improvement over previous constructions of flushing valves. The assembling together of all the parts (except the joint between the bell and the flange 25) by means of threads, thereby entirely eliminating the use of solder, conduces greatly to the durability and consequent permanent efficiency of the valve. One important advantage of the present construction lies in the fact that the plunger rod 17 being threaded into the centerpiece 28 and into the top of the bell simultaneously, holds the top of the bell a predetermined distance from the top of the centerpiece so that the eyepiece 12 can be jammed down against the top of the bell under considerable pressure without liability of crushing in the bell, and so in like manner the bell is lifted by stresses transmitted through the stem or rod 17, thereby avoiding any distortion or racking of the bell, as a result of which the joints of the bell are not liable to be loosened in use. A further advantage of the present construction lies in the fact that the centerpiece is a relatively heavy casting and that it serves as a backbone or skeleton for supporting the other parts of the flushing valve.

The various parts constituting the flushing valve of the present invention not only produce a durable and efficient valve when they are assembled, but they are so constructed that they may be made cheaply and in large quantities by a few simple processes of manufacture. The bell 10 is, as before stated, drawn or spun into form. The bottom plate 24 is stamped or spun into shape. The centerpiece is a casting which may be finished by a simple, automatic screw machine process, and the rod 17 is easily made in a screw machine. It is thus seen that all the parts are adapted for quantity production by means of dies, molds, or turret machine work so that when the parts are made they can be readily assembled

without any further mechanical work other than screwing them together in order to assemble them into a completed valve.

Having thus described the invention what is claimed as new is:

1. A flushing valve for water closets comprising a hollow body portion having an inlet and an outlet, a valve for normally closing the inlet, and a float connected with the valve consisting of a bell and a bottom plate, said bottom plate having an upturned marginal flange for connection with the bell, and a downturned central flange.
2. A flushing valve for water closets comprising a hollow body portion having an inlet and an outlet, a valve for normally closing the inlet, and a float connected with the valve consisting of a bell and a bottom plate, said bottom plate having an upturned marginal flange for connection with the bell, and a downturned central flange, a relatively heavy centerpiece screwed into the central flange and having an opening by which water may flow out of the float and into the hollow body portion.
3. A flushing valve for water closets comprising a hollow body portion having an inlet and an outlet, a valve for normally closing the inlet, a float connected with the valve consisting of a bell and a bottom plate, said bottom plate having a central

aperture, a centerpiece screwed into the central aperture, and a rod which screws into the centerpiece and into the top of the bell.

4. A flushing valve for water closets comprising a hollow body portion having an inlet and outlet, a valve for normally closing the inlet, a float connected with the valve consisting of a bell and a bottom plate, said bottom plate having an upturned marginal flange and a downturned central flange, a centerpiece screwed into the central flange, and a rod which screws into the centerpiece and into the top of the bell.

5. A flushing valve for water closets comprising a hollow body portion having an inlet and an outlet, a valve for normally closing the inlet, a float connected with the valve consisting of a bell and a bottom plate, said bottom plate having an upturned marginal flange into which the bell fits and a downturned central flange, a centerpiece screwed into the central flange, a rod screwed into the centerpiece and into the top of the bell, an eye-piece screwed onto the end of the plunger rod and taking against the top of the bell, and a nut screwed onto the bottom of the centerpiece for holding the valve against the underside of the bottom plate and the centerpiece in the bottom plate.
